CALL-REGISTERED SIGNALS FOR ELEVATOR SYSTEMS

William F. Eames, Westfield, N. J., assignor to Westinghouse Electric Corporation, East Pittsburgh, Pa., a corporation of Pennsylvania

Application August 17, 1953, Serial No. 374,460

11 Claims. (Cl. 340—19)

This invention relates to signaling devices for indicating that a predetermined operation has been performed, and it has particular relation to call-registered signals for indicating that a call for service is registered in an elevator system.

In various systems, it is a practice to provide signals for indicating that a predetermined operation has been effected. For example, in an elevator system it is a practice to provide a plurality of floor-station units, each operable for registering a call for elevator service for the associated floor. In order to indicate that a call for service is registered, a suitable signal may be associated with each of the floor-station units.

In a typical elevator system, the floor-station unit may take the form of a push-button station located at each of the floors served by the elevator car. In order to register a call for elevator service, a prospective or intending passenger at one of the floors may operate the push-button for such floor. The registration of the call may be indicated by a suitable signal, such as a lamp located adjacent the operated push-button.

In prior art systems, it has been the practice to run an electrical conductor for each lamp associated with a push-button to a central equipment room, such as a penthouse, containing control equipment for the elevator system. The requirement of such conductors adds materially to the cost and complexity of the elevator system.

In accordance with the invention, a signal for indicating a predetermined operation is provided which requires a minimum of wiring. In a preferred embodiment of the invention, each push-button employed in an elevator system for registering a call for service has a terminal which is connected to a common bus only during the registration of a call for service. By establishing an electric voltage between the bus and an electroconductive member adjacent each of the push-buttons, a signal may be connected between the bus and the electrically conductive member with a minimum of wiring. In a preferred embodiment of the invention, the electroconductive member is ground.

The signal conveniently may be in the form of a lamp and preferably is a cold-cathode gaseous-discharge lamp. Although the lamp may be energized from a source of electric energy employed for energizing the control circuits of the elevator system, generally a direct-current source, preferably a separate source of alternating voltage is provided for the lamps. In order to prevent the discharge of direct current through the lamps, a suitable blocking device, such as a capacitor, is provided for blocking the flow of direct current through the lamp while permitting the flow of current derived from the source of alternating voltage.

If the lamps are to be energized from the direct-current source employed for the control circuits of the elevator system, blocking devices in the form of rectifiers may be employed for eliminating "sneak" circuits.

It is, therefore, an object of the invention to provide an

2

improved signaling mechanism for indicating that a predetermined operation has been performed.

It is a further object of the invention to provide an elevator system having floor-station units operable for registering calls for elevator service and having signal devices for indicating the registration of a call for service, wherein the wiring for each of the signal devices is confined to an associated floor-station unit.

It is also an object of the invention to provide an elevator system having floor push-buttons operable for registering calls for elevator service and having a signal device for each of the push-buttons, wherein a source of direct-current energy is employed for circuits associated with the push-button units and wherein a source of alternating electric energy is provided for the signal devices.

It is a still further object of the invention to provide a system as set forth in the preceding paragraph wherein each signaling device is in the form of a cold-cathode gaseous-discharge tube, and wherein each of the signaling devices is energized through a direct-current blocking device.

Other objects of the invention will be apparent from the drawings taken in conjunction with the following description, in which:

25 Figure 1 is a schematic view with circuit shown in straight-line form of an elevator system embodying the invention; and,

30 Figs. 2, 3 and 4 are schematic views with circuits shown in straight-line form illustrating modifications of the invention.

35 The invention may be incorporated in any elevator system having floor-station units, such as push-buttons, for registering calls for elevator service. For the purpose of illustration, it will be assumed that the invention is added to the elevator system disclosed in my Patent 2,501,320 which was issued March 21, 1950.

40 The present Fig. 1 is intended to employ the complete system of my aforesaid patent with certain additions which are shown in heavy lines. Since the additions may be illustrated as applied to Fig. 4 of my aforesaid patent, such Fig. 4 is reproduced in its entirety in the present Fig. 1.

45 Apparatus common to my aforesaid patent and to the present Fig. 1 may be listed as follows:

Apparatus individual to car A

S—floor call stopping relay

M3—contacts of car running relay

50 X3 and X4—contacts of down direction preference relay

W3 and W4—contacts of up direction preference relay

L+3, L—3—direct current buses

b2 to b6, c2 to c7, f2 to f7, g2 to g7—contact segments on floor selector

55 32, 33, 41, 42—brushes of floor selector

Apparatus common to both cars

2DR to 7DR—down call-storing relays

2UR to 6UR—up call-storing relays

60 2DRN to 7DRN, 2URN to 6URN—cancellation coils for storing relays

2D to 7D—down floor buttons

2U to 6U—up floor buttons

65 For a complete description of the apparatus set forth in the above list, reference may be made to my aforesaid patent. However, to facilitate an understanding of the invention, a brief résumé of typical operations will now be given.

70 The circuits illustrated in detail in Fig. 1 are intended for operation to register calls for elevator service from the floors of a structure or building served by the elevator cars. For example, if a prospective passenger at

the fourth floor desires to register a call for service in the up direction he presses the push-button 4U to connect the up call-storing relay 4UR across the buses L+3 and L-3. The energization of the up call-storing relay 4UR results in closure of the holding contacts 4UR1 to establish a holding circuit around the push-button 4U.

The first available elevator car to approach the fourth floor while set for travel in the up direction stops at the fourth floor to answer the call for service. For example, if the elevator car A is set for travel in the up direction and is approaching the fourth floor, the brush 32 engages the contact segment b4 to complete the following stopping circuit:

L+3, 4UR1, b4, 32, W3, S, L-3

The energization of the floor call stopping relay S conditions the elevator car A to stop at the fourth floor.

If the elevator car A stops at the fourth floor, the brush 33 engages the contact segment c4 to complete the following cancel circuit:

L+3, 4UR1, 4URN, c4, 33, W4, M3, L-3

The energization of the canceling coil 4URN resets the up call-storing relay 4UR, and the relay opens its make contacts 4UR1 to interrupt the energization of the relay and of the canceling coil.

It will be understood that the up call-storing relay 4UR usually would be located in the penthouse of the building or structure served by the elevator car, whereas the push-button 4U would be located in a floor-station unit at the fourth floor of the structure or building. One terminal of the push-button would be connected to the relay by means of an electroconductive element or wire 4UW.

Each of the up push-buttons 2U to 6U similarly is associated with its up call-storing relay. In each case, the electroconductive element is identified by the letter W preceded by the reference character employed for the associated push-button.

In a similar manner, each of the push-buttons 2D to 7D may be pressed to register a call for elevator service in the down direction. For example, if the push-button 4D is pressed, the down call-storing relay 4DR is connected across the buses L+3 and L-3 for energization. This relay closes its make contacts 4DR1 to establish a holding circuit around the push-button. The first available elevator car set for travel in the down direction which approaches the fourth floor is stopped in response to the registered call. For example, if the elevator car A is the first available car to reach the fourth floor under these conditions, the following stopping circuit is completed:

L+3, 4DR1, g4, 42, X3, S, L-3

The energization of the floor call stopping relay S stops the elevator car A at the fourth floor in a manner which is clearly set forth in my aforesaid patent.

As the elevator car A stops at the fourth floor, the brush 41 engages the contact segment f4 to complete the following canceling circuit:

L+3, 4DR1, 4DRN, f4, 41, X4, M3, L-3

The energization of the cancellation coil resets the down call-storing relay 4DR which opens its make contacts 4DR1 to de-energize the relay 4DR and the cancelling coil 4DRN.

It will be understood that each of the down call-storing relays may be located in a penthouse, whereas each of the down push-buttons may be located at one of the floors served by the elevator cars. Each of the down call-storing relays is connected to a terminal of its associated push-button in the manner discussed for the up call-storing relays. Thus, the relay 4DR has a terminal connected to a terminal of the push-button 4D through the electroconductive element 4DW.

In order to indicate each registration of a call for service, a source of voltage is connected across the bus

L+3 and an electroconductive member which extends adjacent each of the aforesaid station units or push-buttons. Although the electroconductive member may be in the form of a wire, it will be assumed that ground 5 serves as the electroconductive member. In elevator installations, it is common practice to place wiring in electroconductive conduit which extends adjacent each of the push-buttons. Consequently, such conduit may serve adequately as the electroconductive member or ground.

10 As a further example, most large buildings have steel frameworks which extend adjacent the push-buttons associated with elevator systems installed in such buildings. Consequently, if desired, the steel framework may be employed as the electroconductive member or ground.

15 The source of voltage applied between the bus L+3 and the electroconductive member or ground may be similar to that appearing between the bus L+3 and L-3. Preferably, however, the voltage is of a type permitting segregation of currents derived from the buses from

20 circuits associated with the source of voltage. In a preferred embodiment of the invention, the source of voltage may be derived from an alternating source SV having a frequency selected from a wide range of frequencies. As a specific example, a frequency of 1,000 cycles per second

25 is suitable. The alternating source SV is connected across the primary winding of a transformer TR. The transformer has a secondary winding connected between the bus L+3 and the aforesaid electroconductive member or ground GR. Preferably, direct current is prevented

30 from flowing through the secondary winding of the transformer TR by inserting in series therewith a suitable blocking device, such as a capacitor CA. The capacitor is selected to offer a low impedance to current having a frequency of 1,000 cycles per second.

35 Each of the push-buttons has associated therewith a signal device which preferably is in the form of a lamp. Each lamp is designated by the letter L preceded by the reference character of the push-button with which the lamp is associated. For example, the lamp 4UL is associated with the push-button 4U.

Each of the lamps has one terminal connected to that terminal of the associated push-button which is connected to the associated call-storing relay. The remaining terminal of the lamp is connected to the electroconductive member or ground GR. Preferably, each

45 of the lamps is energized through a circuit which includes a blocking device for blocking current produced by the direct voltage appearing across the bus L+3 and L-3. As shown in Fig. 1, the blocking device may take the form of a capacitor connected in series with each of the lamps. Each of the capacitors is designated by the letter C preceded by the reference character employed for the associated push-button. For example, the capacitor 4UC is connected in series with the lamp 4UL

50 associated with the push-button 4U. It will be noted that the circuit for the lamp 4UL extends between the electroconductive element 4UW and ground. A similar energizing circuit is associated with each of the lamps for each of the push-buttons.

60 Although the lamp may be of the incandescent filament type, preferably it is a low-wattage cold-electrode gaseous-discharge lamp. Lamps of this type sometimes are referred to as neon lamps if the gas contained therein is primarily neon.

65 If desired, the lamps associated with the push-buttons may have distinct colors. For example, lamps associated with the up push-buttons may be designed to produce a green color, whereas lamps associated with down push-buttons may be designed to produce a red color. Further distinctions may be introduced by properly shaping the visible light. For example, each of the lamps may pass through a mask or stencil giving the light the outline of an arrow pointed in the direction of desired travel. Such masking and coloring of light for indicating lamps is well known in the art.

It is believed that the operation of the lamps now may be set forth. Let it be assumed that a prospective passenger at the fourth floor presses the push-button 4U to register a call for service in the up direction. As a result of such pressure of the push-button, the up call-storing relay 4UR is energized and closes its holding contacts 4UR1. It will be noted that the lamp 4UL now is energized through a circuit which extends from one terminal of the secondary winding of the transformer TR through the capacitor CA, the bus L+3, the contacts 4UR1, part of the electroconductive element 4UW, the capacitor 4UC, the lamp 4UL and ground back to the remaining terminal of the secondary winding. The energization of the lamp continues until the relay 4UR is reset to open its contacts 4UR1. Each of the lamps is similarly energized in response to operation of its associated push-button.

It should be noted that the wiring for each of the lamps need not extend beyond the associate push-button station. Consequently, a minimum of cost and complexity is introduced by the lamps illustrated in Fig. 1.

As previously pointed out, ground GR may be employed as an electroconductive member extending adjacent each of the lamps. If desired, a separate wire may be employed in place of ground. Such a wire GRW is illustrated in Fig. 4. The system of Fig. 4 may be identical to that of Fig. 1, except for the replacement of the ground connection GR by the wire GRW. For this reason, a further discussion of Fig. 4 appears to be unnecessary.

If desired, the same source of energy may be employed for the various relays and for their lamps. Thus, in Fig. 2, the relays 6UR and 5UR together with the canceling coils 6URN and 5URN are again associated with the buses L+3 and L-3 in the manner discussed with reference to Fig. 1. However, a conductor or wire L-3A extends from the bus L-3 and passes adjacent each of the push-button stations of the elevator system. Consequently, the direct voltage appearing between the buses L+3 and L-3 also appears between the bus L+3 and the wire L-3A. Each of the push-buttons has associated therewith a lamp for the purpose of indicating registration of a call for service. For example, lamps 6ULA and 5ULA are associated respectively with the push-buttons 6U and 5U. These lamps may be cold-cathode gaseous-discharge lamps of the type discussed with reference to Fig. 1. However, for present purposes it will be assumed that these lamps are incandescent filament lamps.

By inspection of Fig. 2, it will be observed that the lamp 6ULA is connected between the wires 6UW and L-3A. Preferably, this connection includes a rectifier 6UE to permit flow of current through the lamp from the positive bus, but to prevent flow of current in the opposite direction.

When the push-button 6U is pressed to register a call for service, closure of the make contact 6UR1 completes the following energizing circuit for the lamp:

L+3, 6UR1, 6UW, 6UE, 6ULA, L-3A, L-3

The rectifier 6UE prevents the flow of currents which may result in improper operation of the control circuits. Such currents are referred to in the art as "sneak" currents.

Each lamp is similarly energized by operation of its associated push-button. For example, if the push-button 5U is operated, its associated lamp is energized through the circuits:

L+3, 5UR1, 5UW, 5UE, 5ULA, L-3A, L-3

Each of the rectifiers is identified by the reference character E preceded by the reference character employed for the associated push-button. Conveniently, the rectifiers may be of the barrier-layer type, such as a copper oxide rectifier or a selenium rectifier.

In some cases, it may be feasible to employ one lamp

for a pair of push-buttons. For example, in Fig. 3 the push-button 6U is associated with the call-storing relay 6UR, the lamp 6ULA, and the rectifier 6UE in the same manner discussed with reference to Fig. 2. Fig. 3 also shows the down push-button 6D with its down call-storing relay 6DR and its canceling coil 6DRN associated with the buses L+3 and L-3 in the same manner discussed with reference to Fig. 1.

In the embodiment of Fig. 3, the lamp 6ULA, when illuminated, is intended to indicate the registration of either an up floor call, a down floor call, or of both an up floor call and down floor call for the sixth floor. To this end, the electroconductive element 6DW is connected through a rectifier 6DE to the terminal of the lamp 6ULA intermediate the lamp and the rectifier 6UE. Consequently, if the push-button 6D is pressed, the following energizing circuit is established for the lamp:

L+3, 6DR1, 6DW, 6DE, 6ULA, L-3A, L-3

The rectifier 6DE is poled to permit current to flow from the positive bus L+3 through the lamp to the negative bus L-3, but not in the reverse direction. The lamp 6ULA in Fig. 3 does not discriminate between up and down registered calls.

Although the invention has been described with reference to certain specific embodiments thereof, numerous modifications falling within the spirit and scope of the invention are possible.

I claim as my invention:

- 30 1. In an elevator system comprising a structure having at least three floors; an elevator car; means mounting the elevator car for movement relative to the structure to serve the floors; a source of electric energy including a first electroconductive element; separate call-registering means for each of the floors; each of the call-registering means for one of the floors comprising separate electro-responsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the associated translating means for controlling the energization of the translating means in accordance with operation of the associated floor-station unit; in combination with a second electro-conductive element extending adjacent said floor-station units; means for establishing an electric voltage between said elements; a separate electro-responsive signal adjacent each of the floor-station units, coupling means adjacent the floor-station unit coupling the signal for each of the floor-station units across the electroconductive member for the associated floor-station unit and the second electroconductive element to establish a signal energizing circuit responsive to the voltage between the member and the last-named element, said last-named coupling means for each signal including a blocking device preventing substantial flow of electric current through the associated signal from the source in more than one direction for each operation of a floor-station unit; the translating unit for each of the floor-station units being effective while in operated condition for maintaining a connection between the first electroconductive element and the electroconductive member for the associated floor-station unit to operate the signal for such associated floor-station unit, whereby operation of any of the translating means is accompanied by operation of the associated signal to indicate that the desired call for service is registered.
- 35 2. In an elevator system comprising a structure having at least three floors; an elevator car; means mounting the

2. In an elevator system comprising a structure having a plurality of floors; an elevator car; means mounting the

elevator car for movement relative to the structure to serve the floors; a source of electric energy including a first electroconductive element; separate first call-registering means for each of the floors; each of the call-registering means for one of the floors comprising separate electroresponsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the associated translating means for controlling the energization of the translating means in accordance with operation of the associated floor-station unit; in combination with a second electroconductive element extending adjacent said floor-station units; means for establishing an electric voltage between said elements; second call-registering means similar to the first call-registering means for each of said floors, whereby the first and second call-registering means may be employed for registering calls for elevator service respectively in first and second directions of travel, a separate electroresponsive signal for each of the floors adjacent the floor-station units for the associated floor, means coupling the signal for each of the floors in a first circuit across the electroconductive member for the associated floor unit for the first call registering means and the electroconductive element and in a second circuit across the electroconductive member for the associated floor unit for the second call registering means and the electroconductive element, and first and second rectifier means in said first and second circuits respectively, said rectifier means permitting current to flow in the associated circuits only in a predetermined direction through the signal.

3. An elevator control system comprising a plurality of elevator cars; a plurality of landings; a first source of voltage supply; a plurality of control switches, one at each of the respective landings operable by intending passengers; a plurality of stopping mechanisms one for each car for causing the stopping of the associated cars at the respective landings; and means responsive to an actuation of a control switch for effecting only one energization of one of the stopping mechanisms from said first source of voltage supply; a second source of voltage supply; a signal lamp associated with said actuated control switch; and means responsive to said actuation of said control switch for energizing said signal lamp from said second voltage supply, whereby said signal indicates the actuation of said control switch until an elevator car stops at the landing associated with such control switch.

4. In an elevator system comprising a structure having a plurality of floors; an elevator car; means mounting the elevator car for movement relative to the structure to serve the floors; a source of electric energy including a first electroconductive element; separate first call-registering means for each of the floors; each of the call-registering means for one of the floors comprising separate electroresponsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit; second call-registering means similar to the first call-registering means for each of said floors, whereby the first and second call-registering means may be employed for registering calls for elevator service respectively in first

and second directions of travel, a separate electroresponsive signal for each of the floors adjacent the floor station units for the associated floor, and means responsive to operation of each of the two floor station units for a floor 5 to register a call for operatively energizing the signal for the last-named floor.

5. In an elevator system comprising a structure having at least three floors; an elevator car; means mounting the elevator car for movement relative to the structure to 10 serve the floors; a source of electric energy including a first electroconductive element; separate call-registering means for each of the floors; each of the call-registering means for one of the floors comprising separate electroresponsive translating means for each of the floors each 15 effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the 20 associated translating means for controlling the energization of the translating means in accordance with operation of the associated floor-station unit; in combination with a second electroconductive element extending adjacent said floor-station units; means for establishing an electric 25 voltage between said elements; a separate electroresponsive signal adjacent each of the floor-station units, coupling means adjacent the floor-station unit coupling the signal for each of the floor-station units across the electroconductive member for the associated floor-station unit 30 and the second electroconductive element to establish a signal energizing circuit responsive to the voltage between the member and the last-named element, said last-named coupling means for each signal including a blocking device preventing substantial flow of electric current 35 through the associated signal from the source in more than one direction for each operation of a floor-station unit; the translating unit for each of the floor-station units being effective while in operated condition for maintaining a connection between the first electroconductive element and the electroconductive member for the associated floor-station unit to operate the signal for such associated floor-station unit, whereby operation of any of the translating means is accompanied by operation of the associated signal to indicate that the desired call for service is 40 registered, in combination with means responsive to stopping of the elevator car at any of the floors in response to a call registered by the call-registering means for the last-named floor for resetting the last-named call-registering means and thereby resetting the signal for the last-named call-registering means.
- 45 6. In an elevator system comprising a structure having at least three floors; an elevator car; means mounting the elevator car for movement relative to the structure to serve the floors; a source of electric energy including a first electroconductive element; separate call-registering means for each of the floors; each of the call-registering means for one of the floors comprising separate electroresponsive translating means for each of the floors each 50 effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the associated translating means for controlling 55 the energization of the translating means in accordance

with operation of the associated floor-station unit; in combination with a second electroconductive element extending adjacent said floor-station units; means for establishing an electric voltage between said elements; a separate electroresponsive signal adjacent each of the floor-station units, coupling means adjacent the floor-station unit coupling the signal for each of the floor-station units across the electroconductive member for the associated floor-station unit and the second electroconductive element to establish a signal energizing circuit responsive to the voltage between the member and the last-named element, said last-named coupling means for each signal including a blocking device preventing substantial flow of electric current through the associated signal from the source in more than one direction for each operation of a floor-station unit; the translating unit for each of the floor-station units being effective while in operated condition for maintaining a connection between the first electroconductive element and the electroconductive member for the associated floor-station unit to operate the signal for such associated floor-station unit, whereby operation of any of the translating means is accompanied by operation of the associated signal to indicate that the desired call for service is registered, the electric voltage being at a frequency differing from the frequency of the source, each of said blocking devices comprising discriminating means having a high impedance to the source and a low impedance to the voltage.

7. In an elevator system comprising a structure having at least three floors; an elevator car; means mounting the elevator car for movement relative to the structure to serve the floors; a source of electric energy including a first electroconductive element; separate call-registering means for each of the floors; each of the call-registering means for one of the floors comprising separate electroresponsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the associated translating means for controlling the energization of the translating means in accordance with operation of the associated floor-station unit; in combination with a second electroconductive element extending adjacent said floor-station units; means for establishing an electric voltage between said elements; a separate electroresponsive signal adjacent each of the floor-station units, coupling means adjacent the floor-station unit coupling the signal for each of the floor-station units across the electroconductive member for the associated floor-station unit and the second electroconductive element to establish a signal energizing circuit responsive to the voltage between the member and the last-named element, said last-named coupling means for each signal including a blocking device preventing substantial flow of electric current through the associated signal from the source in more than one direction for each operation of a floor-station unit; the translating unit for each of the floor-station units being effective while in operated condition for maintaining a connection between the first electroconductive element and the electroconductive member for the associated floor-station unit to operate the signal for such associated floor-station unit, whereby operation of any of the translating means is accompanied by operation of the associated signal to indicate that the desired call for service is registered, the second electroconductive element being at ground potential.

8. In an elevator system comprising a structure having at least three floors; an elevator car; means mounting

the elevator car for movement relative to the structure to serve the floors; a source of electric energy including a first electroconductive element; separate call-registering means for each of the floors; each of the call-registering means for one of the floors comprising separate electroresponsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the associated translating means for controlling the energization of the translating means in accordance with operation of the associated floor-station unit; in combination with a second electroconductive element extending adjacent said floor-station units; means for establishing an electric voltage between said elements; a separate electroresponsive signal adjacent each of the floor-station units, coupling means adjacent the floor-station unit coupling the signal for each of the floor-station units across the electroconductive member for the associated floor-station unit and the second electroconductive element to establish a signal energizing circuit responsive to the voltage between the member and the last-named element, said last-named coupling means for each signal including a blocking device preventing substantial flow of electric current through the associated signal from the source in more than one direction for each operation of a floor-station unit; the translating unit for each of the floor-station units being effective while in operated condition for maintaining a connection between the first electroconductive element and the electroconductive member for the associated floor-station unit to operate the signal for such associated floor-station unit, whereby operation of any of the translating means is accompanied by operation of the associated signal to indicate that the desired call for service is registered, each of said blocking devices including rectifier means permitting flow of current in the associated circuit in only one direction.

9. In an elevator system comprising a structure having at least three floors; an elevator car; means mounting the elevator car for movement relative to the structure to serve the floors; a source of electric energy including a first electroconductive element; separate call-registering means for each of the floors; each of the call-registering means for one of the floors comprising separate electroresponsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the associated translating means for controlling the energization of the translating means in accordance with operation of the associated floor-station unit; in combination with a second electroconductive element extending adjacent said floor-station units; means for establishing an electric voltage between said elements; a separate electroresponsive signal adjacent each of the floor-station units, coupling means adjacent the floor-station unit coupling the signal for each of the floor-station units across the electroconductive member for the associated floor-station unit and the second electroconductive element to establish a signal energizing circuit responsive to the voltage between the member and the last-named element, said last-named coupling means for each signal including a blocking device preventing substantial flow of electric current through the associated signal from the source in more than one direction for each operation of a floor-station unit; the translating unit for each of the floor-station units being effective while in operated condition for maintaining a connection between the first electroconductive element and the electroconductive member for the associated floor-station unit to operate the signal for such associated floor-station unit, whereby operation of any of the translating means is accompanied by operation of the associated signal to indicate that the desired call for service is registered, the second electroconductive element being at ground potential.

10. In an elevator system comprising a structure having at least three floors; an elevator car; means mounting

last-named coupling means for each signal including a blocking device preventing substantial flow of electric current through the associated signal from the source in more than one direction for each operation of a floor-station unit; the translating unit for each of the floor-station units being effective while in operated condition for maintaining a connection between the first electroconductive element and the electroconductive member for the associated floor-station unit to operate the signal for such associated floor-station unit, whereby operation of any of the translating means is accompanied by operation of the associated signal to indicate that the desired call for service is registered, each of the signals comprising a cold-electrode, gaseous-discharge lamp.

10. In an elevator system comprising a structure having at least three floors; an elevator car; means mounting the elevator car for movement relative to the structure to serve the floors; a source of electric energy including a first electroconductive element; separate call-registering means for each of the floors; each of the call-registering means for one of the floors comprising separate electroresponsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit, said coupling means including an electroconductive member extending between the floor-station unit and the associated translating means for controlling the energization of the translating means in accordance with operation of the associated floor-station unit; in combination with a second electroconductive element extending adjacent said floor-station units; means for establishing an electric voltage between said elements; a separate electroresponsive signal adjacent each of the floor-station units, coupling means adjacent the floor-station unit coupling the signal for each of the floor-station units across the electroconductive member for the associated floor-station unit and the second electroconductive element to establish a signal energizing circuit responsive to the voltage between the member and the last-named element, said last-named coupling means for each signal including a blocking device preventing substantial flow of electric current through the associated signal from the source in more than one direction for each operation of a floor-station unit; the translating unit for each of the floor-station units being effective while in operated condition for maintaining a connection between the first electroconductive element and the electroconductive member

for the associated floor-station unit to operate the signal for such associated floor-station unit, whereby operation of any of the translating means is accompanied by operation of the associated signal to indicate that the desired call for service is registered, the source supplying direct current, and the electric voltage being an alternating voltage, each of said signals comprising a lamp, and each of the blocking devices including a capacitor capable of blocking flow of direct current but offering a low impedance to alternating current derived from said alternating voltage.

11. In an elevator system comprising a structure having a plurality of floors; an elevator car; means mounting the elevator car for movement relative to the structure to serve the floors; a source of electric energy including a first electroconductive element; separate first call-registering means for each of the floors; each of the call-registering means for one of the floors comprising separate electroresponsive translating means for each of the floors each effective when operated for registering a call from the associated one of the floors, a floor-station unit spaced from the translating means and operable by a person desiring to register a call for elevator services for the associated one of the floors, and coupling means coupling the floor-station unit and the associated translating means to the source for controlling the operation of the translating means in response to operation of the floor-station unit; second call-registering means similar to the first call-registering means for each of said floors, whereby the first and second call-registering means may be employed for registering calls for elevator service respectively in first and second directions of travel, a separate electroresponsive signal for each of the floors adjacent the floor-station units for the associated floor, and means responsive to operation of each of the two floor-station units for a floor to register a call for operatively energizing the signal for the last-named floor, in combination with means responsive to arrival of the elevator car adjacent a floor to answer a call registered by operation of only one of the translating means for the last-named floor for resetting the last-named translating means and the signal associated with the last-named translating means.
